UNITED STATES PATENT OFFICE.

ARTHUR B. SPERRY, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE-EXCHANGE SYSTEM.

1,221,917.

Specification of Letters Patent.

Patented Apr. 10, 1917.

Application filed September 2, 1916. Serial No. 118,250.

To all whom it may concern:

Be it known that I, ARTHUR B. SPERRY, a citizen of the United States, residing at New York, in the county of New York and State of New York, have invented certain new and useful Improvements in Telephone-Exchange Systems, of which the following is a full, clear, concise, and exact description.

- 10 This invention relates to telephone exchange systems wherein calling lines are associated with idle connecting circuits by automatic finder switches. In such systems the finders are usually common to the groups, 15 and when a finder normally associated with a given group is being set from another group, it is necessary to remove the control of such finder from its group to prevent interference.
- 20 In accordance with this invention, this is accomplished by providing a means associated with each finder, which, when such finder is being set from another group than that to which it is normally allotted, renders 25 inoperative all the line relays of the group to which the finder belongs.

The invention will be more readily understood when described with reference to the accompanying drawing, which shows 30 only so much of a telephone exchange system as is necessary for a comprehension of the invention. Each line is provided at the central office with a line relay 14 and a cut-off relay 15, and with multiple terminals t , t' , t'' in a group of finders. These multiples are adapted to be wiped over by a set of brushes b , b' , b'' , one for each group of lines. Upon the initiation of a call, the finder brush shaft is given a primary movement 35 under control of a magnet PM to position a set of brushes in operative relation to the calling group, and thereafter a secondary movement under control of the magnet SM to drive the brushes over such group in 40 search of the calling line.

The invention will be clearly understood from a description of the operation.

Upon the removal of the receiver at substation A, the following circuit is closed to 50 energize the line relay 14: free pole of battery, resistance 10, left armature and back contact of slow relay 11 common to the group of lines to which substation A belongs, conductors 12 and 13, left winding of line relay 14, outer armature of cut-off re-

lay 15, line conductor 6, through the telephonic apparatus at substation A, line conductor 7, inner armature of cut-off relay 15, right winding of line relay 14 to ground. Assuming that the finder shown is the one allotted to the group to which substation A belongs, the commutator brush 20 is in contact with commutator segment 21 of said group, and a set of brushes b , b' , b'' is in operative relation to the group of terminals containing those of the calling line t , t' , t'' . The following circuit is therefore immediately closed, upon the energization of line relay 14, to pass the side switch into position 2 to initiate the secondary movement of the finder: free pole of battery, magnet PM, sideswitch arm 5 and its first contact, escape magnet 18, conductor 31, arm 3 and its first contact, conductors 40, 22, brush 20, segment 21, conductors 23, 24, 25 and 26 to ground at the right armature and front contact of relay 14. In position 2 the following circuit is closed for the secondary magnet SM to drive the brushes over the calling group: free pole of battery, magnet SM and its armature and back contact, arm 4 and its second contact, armature and back contacts of magnets 18 and RM, conductor 42, slow relay 11 to ground at the right armature and front contact of relay 16, which became energized when relay 14 attracted its right armature. In position 2, side-switch arms 5 and 2 connect the escapement magnet to the brush b' , over the armature and back contact of the test relay 28. In passing over lines that are engaged in conversation, the escape magnet 18 cannot become energized, due to its circuit being opened by the relay 28 which is energized over the following circuits as such lines are encountered: free pole of battery, left winding of relay 28, conductors 29, 31, arm 3 and its second contact, brush b'' , terminal t'' of such lines to ground over the side-switch arms 3 and third contacts of the finders involved in such connections. This relay is maintained energized by its right winding as the brushes pass between terminals in order to prevent the grounded right armature of relay 16 from being extended to brush b' and thus interfering with existing connections. This circuit is as follows: free pole of battery, right winding of relay 28, conductor 50, armature and back contact of magnet SM, arm 4 and its second contact, armatures and back contacts 100

105

110

of magnets 18 and RM, conductor 42, relay 11, right armature of relay 16 to ground. When the calling line is reached, the following circuit is closed for the escapement 5 magnet 18 to pass the side switch to position 3; free pole of battery, magnet SM, arm 5 and its second contact, magnet 18, conductors 31, 29, armature and back contact of relay 28, arm 2 and its second contact, brush 10 b', terminal t', conductors 32, 33 to ground at the left armature and front contact of relay 14. The escape magnet 18, in energizing, passes the side switch into position 3. Arm 5, in passing out of position 2, opens the circuit of secondary magnet SM, thus stopping 15 the finder with the brushes b, b', b² in engagement with calling line terminals t, t', t². Arm 3, in position 3, grounds multiple t² to operate the cut-off relay 15, and causes this 20 line to test busy to other finders and connectors. Cut-off relay 15, in energizing, de-energizes the line relay 14, which in retracting its left armature, removes ground from multiples t' to render substation A non-calling 25 in the other finders in which it appears, and in retracting its right armature, removes ground from the multiple commutator segments 21 to render the group containing substation A non-calling in other finders 30 in which it appears, and de-energizes relay 16 which reconnects the in-starter wire 37 to side-switch arm 4, which now, in position 3, is connected to the out-starter wire 34 leading to the next finder.

35 Assume now that a line belonging to another group to which the relays 11', 16' are individual, initiates a call, and that the finder apportioned thereto is busy, and that the finder apportioned to the group to which 40 substation A belongs is the next idle finder. The energization of the line relay of such line, corresponding to 14, operates the relay 16' of such group, with the result that the following circuit is closed to initiate the primary movement of the finder: ground, right armature and front contact of relay 16', slow relay 11', conductor 35, side-switch arm 36 and its third contact, conductor 37, right armature and back contact of relay 16, slow relay 11, armature and back contact of 45 magnets RM and 18, side-switch arm 4 and its first contact, armature and back contact of primary magnet PM, to free pole of battery. Slow relay 11, in attracting its left armature, removes the connection of battery to all the line relays 14 of the group to which substation A belongs. Primary magnet PM makes and breaks the circuit traced until the commutator brush 20 reaches the commutator multiple segment of the calling group, when the following circuit is closed for the escape magnet 18 to pass the side switch to position 2; free pole of battery, magnet PM, arm 5 and its first contact, magnet 18, conductor 31, arm 3 and its first con-

tact, conductors 40, 22, brush 20, commutator multiple segment of the calling group corresponding to 21, conductors 23, 24, 25, 26, right armature and front contact of relay 14 of the calling line to ground. In position 70 2, the following circuit is closed for the secondary magnet SM to drive the brushes b, b', b² over the terminals of the calling group; free pole of battery, magnet SM, its armature and back contact, arm 4 and its 75 second contact, armatures and back contacts of magnets 18 and RM, slow relay 11, right armature and back contact of relay 16, conductor 37, arm 36 and its third contact, conductor 35, relay 11', right armature and 80 front contact of relay 16' to ground.

As hereinbefore described, in passing over lines that are engaged in conversation, the escapement magnet 18 cannot become energized, due to its circuit being opened by the 85 relay 28, which is energized as such lines are encountered. When, however, the calling line is reached, the following circuit is closed for the escape magnet 18 to pass the side switch into position 3: free pole of battery, 90 magnet SM, arm 5 and its second contact, magnet 18, conductors 31, 29, armature and back contact of relay 28, conductor 41, arm 2 and its second contact, brush b', terminal t', conductors 32, 33, left armature and front 95 contact of the line relay of the calling line to ground.

From this point on, the operation is the same as that already traced, the cut-off relay 100 of the calling line being operated as the side-switch arm 3 moves into position 3. This relay de-energizes the line relay, which in turn de-energizes slow relays 11' and 11. Relay 11, in retracting its left armature, restores the connection of battery to the line 105 relays of the group to which substation A belongs, and relay 11' restores the connection of battery to the line relays of its group.

What is claimed is:

1. In a telephone exchange system, the 110 combination with a group of telephone lines, line relays therefor, an automatic finder switch apportioned to said group, driving means for said switch, means for rendering said driving means operative including the 115 line relays of such group, a second group of lines, line relays therefor, means controlled by any of said line relays for actuating said driving means, and means operated when said finder is moving under control of a line 120 in said second group for preventing the operation of the line relays of the group to which said finder is apportioned.

2. In a telephone exchange system, the 125 combination with a group of telephone lines, line relays therefor, a source of current with which said line relays are normally connected, an automatic finder switch apportioned to said group, driving means for said switch, means for rendering said driving means op- 130

erative including the line relays of such group, a second group of lines, line relays therefor, means controlled by any of said line relays for actuating said driving means, 5 and a relay operated when said finder is being set from said second group to remove the connection of said source of current from

the line relays of the group to which said finder is apportioned.

In witness whereof, I hereunto subscribe my name this 1st day of September A. D., 1916.

ARTHUR B. SPERRY.
